INVENTOR

BY *Victor J. Evans*

ATTORNEY

UNITED STATES PATENT OFFICE.

APOLLONY ZANELLA, OF HELENA, MONTANA.

BUFFER.

Application filed February 5, 1923. Serial No. 617,005.

To all whom it may concern:

Be it known that I, APOLLONY ZANELLA, a citizen of the United States, residing at Helena, in the county of Lewis and Clark 5 and State of Montana, have invented new and useful Improvements in Buffers, of which the following is a specification.

This invention relates to buffers for doors, and contemplates the use of a single strip of 10 yieldable material folded upon itself and associated with the door stop in a novel manner.

The nature and advantages of the invention will be better understood when the following detailed description is read in connection with the accompanying drawing, the invention residing in the construction, combination and arrangement of parts as claimed.

20 In the drawing forming part of this application, like numerals of reference indicate similar parts in the several views, and wherein:

Figure 1 is a side elevation of a buffer.

25 Figure 2 is a transverse sectional view taken on the line 2—2 of Figure 1.

Figure 3 is an enlarged sectional view through the door stop showing the buffer associated therewith.

30 Figure 4 is a sectional view through the door frame showing the door closed and bearing against the buffer.

Referring to the drawing in detail, 10 indicates a door frame forming part of 5 which is the usual door stop or strip 11, the door being indicated at 12. The buffer forming the subject matter of the present invention is adapted to be associated with the door stop or strip 11, and designed to 40 extend along the entire length thereof. The strip 11 is further provided with a long groove 12' to accommodate the buffer in a manner to be presently described.

The buffer is made from a single length of 45 rubber or other suitable yieldable material against which the door, is to close to prevent slamming of the door as will be readily understood, and when the material from which the buffer is formed is thus folded, 50 the ends of the material are brought together in face to face contact as indicated at 13 and received within the metallic member 14 of a U-shaped flange in cross section. The parallel portions of this metallic

member are perforated to provide projections or the like 15 which are embedded in the adjacent portions of the yieldable material 13 to prevent the latter from slipping or becoming casually separated from the metallic member 14. The width of the metallic member is the same as the width of the groove 12', so that when the member is fitted in the groove it is wholly disposed within the latter, with that portion of the yieldable material adapted for use projecting beyond the surface of the door stop or strip 11. As the metallic member is positioned in the groove, certain of the fastening elements 17 used for securing the strip 11 to the door frame are passed through the 70 metallic member 14 and the yieldable material, so that the buffer in its entirety is held fixed with relation to the strip 11 and also to the door frame 10. The buffer is very simple in construction and can be manufactured and sold at a very nominal cost and can be used with any door frame by simply providing a groove 12 in the door stop or strip 11.

While it is believed that from the foregoing description, the nature and advantages of the invention will be readily apparent, I desire to have it understood that I do not limit myself to what is herein shown and described and that such changes may be resorted to when desired as fall within the scope of what is claimed.

Having thus described the invention, I claim:

1. In combination, a door stop comprising a strip secured to the door frame and having a longitudinal groove, a door buffer formed from a single piece of yieldable material folded upon itself, and having its adjacent ends arranged in face to face contact and fitted in said groove, the intermediate portion of said buffer projecting beyond the strip and arranged to be engaged by said door, and the ends of said strip being secured in the groove by the means utilized in securing the strip to the door frame.

2. The combination with a door stop comprising a strip having a longitudinal groove, of a door buffer including a single piece of yieldable material folded upon itself, a metallic member of U-shaped formation in cross section receiving the free edges of said

yieldable member, and means for securing the buffer in its entirety within the groove of the door stop.

3. A door buffer including a length of yieldable material folded upon itself with its marginal edges in face to face contact, a metallic member of U-shaped formation in cross section receiving said edges and co-

extensive in length with the length of said yieldable material, and projections extending inwardly from the metallic member and embedded in the adjacent portions of the yieldable material to hold the parts fixed relatively.

In testimony whereof I affix my signature.

APOLLONY ZANELLA.
